(57) **CLAIM**

The ornamental design for switching equipment, as shown and described.

DESCRIPTION

FIG. 1 is a perspective view of the top, front and left side of switching equipment showing our new design;

FIG. 2 is a front elevational view thereof;

FIG. 3 is a bottom plan view thereof;

FIG. 4 is a top plan view thereof;

FIG. 5 is a right side elevational view thereof; and,

FIG. 6 is a left side elevational view thereof.

The broken line showing of the rear surface is for illustrative purpose and forms no part of the claimed design.
